UNITED STATES PATENT OFFICE.

SIDNEY L. STILES, OF WATSEKA, ILLINOIS.

DESIGN FOR A HINGE.

SPECIFICATION forming part of Design No. 21,558, dated May 24, 1892.

Application filed April 26, 1892. Serial No. 430,781. Term of patent 14 years.

To all whom it may concern:

Be it known that I, SIDNEY L. STILES, a citizen of the United States, residing at Watseka, in the county of Iroquois and State of Illinois,
5 have invented and produced a new and original Design for Hinges, of which the following is a specification, reference being had to the accompanying drawing, forming a part thereof, and in which the figure is a perspective
10 view of a hinge, showing my design.

The leading feature of my design consists

in the curve or bend and the edge contour of the leaf A.

The design includes the curve or bend B and the edge curves or outlines C, as clearly
15 shown.

What I claim is—

The design for a hinge, as shown.

SIDNEY L. STILES.
